UNITED STATES PATENT OFFICE.

HENRI HORMISDAS DUCHESNE AND PASCAL CHARUEST, OF MONTREAL, QUEBEC, CANADA, ASSIGNORS TO BENOIT & MATHIEU, OF MONTREAL, QUEBEC, CANADA.

AMPLIFIER FOR TALKING MACHINES.

Application filed December 24, 1921. Serial No. 524,654.

To all whom it may concern:

Be it known that we, HENRI HORMISDAS DUCHESNE and PASCAL CHARUEST, British subjects, residing at 195 St. Timothee Street, in the city of Montreal, in the Province of Quebec, in the Dominion of Canada, have invented certain new and useful Improvements in Amplifiers for Talking Machines; and we do hereby declare that the following is a true, clear, and exact description of the same.

The present invention relates to improvements in amplifiers for talking machines, which is fully described in the following description and illustrated in the accompanying drawing, in which:

Figure 1 is a side elevation of an amplifier according to the invention.

Figure 2 is a top view of Figure 1.

Figure 3 is an end view.

Like numerals of reference indicate corresponding parts in each figure.

Referring to the drawing, 1 is an amplifier preferably made of plastic or other suitable material and comprising a downwardly and forwardly curved neck or throat portion and a forwardly extending bell portion, both portions being separately formed or cast and having their mutually-contacting ends meeting along an oblique line, as indicated at 3. The throat portion of the amplifier comprises two vertically-

disposed sections 4 and 5 which meet along vertical lines 2, while the bell portion of said amplifier comprises two superposed sections 7 and 8 which meet along horizontal lines 6. The two vertical sections or members 4 and 5 of the throat are preferably counterparts, and the same is also preferably true of the two bell sections or members 7 and 8.

The sections 4, 5, 7, and 8, are glued or otherwise secured together by any suitable substance. A sheet or covering of jute 9, is then glued over said sections to reinforce the structure.

What we claim as our invention is:

An amplifier for talking machines, comprising a curved throat, and a bell connected to said throat and extending horizontally forward from and at an angle to the same: the throat and bell each consisting of a plurality of separately-formed sections of plastic material fastened together, the meeting edges of the sections of said throat and bell being arranged out of coincidence.

Signed at Montreal, Quebec, Canada, this 28th day of November, 1921.

HENRI HORMISDAS DUCHESNE.
PASCAL CHARUEST.
